UNITED STATES PATENT OFFICE.

JANE R. MILLER, OF LOS ANGELES, CALIFORNIA.

DESIGN FOR A TOY BOAT.

Application filed April 25, 1928. Serial No. 26,455. Term of patent 7 years.

To all whom it may concern:

Be it known that I, JANE R. MILLER, a citizen of the United States, residing at Los Angeles, in the county of Los Angeles and State of California, have invented a new, original, and ornamental Design for Toy Boats, of which the following is a specification, reference being had to the accompanying drawing, forming part thereof.

Fig. 2 is a plan view thereof.

I claim:

The ornamental design for a toy boat, as shown.

JANE R. MILLER.
